RAZOR BLADE SHARPENER

Emil H. Schipper, Pasadena, Calif.

Application July 15, 1940, Serial No. 345,569

1 Claim. (Cl. 51—212)

This invention relates generally to sharpeners for double-edged razor blades, and more particularly to sharpeners of the type consisting of a cylindrical or trough-shaped surface on which the blade edge is alined and sharpened by oscillating it in various directions by means of the finger.

Blade sharpeners of this general type are now known. The provision of a truly satisfactory and effective article of this kind, however, presents a considerable problem, all factors of which have not heretofore been appreciated and taken into account. In the first place, for truly effective action, the surface should be extremely hard. I have found that high carbon tool steel, for example, of a carbon content of from .85 to 1.00%, hardened to substantially 64+ Rockwell, will give the desired results. The provision of a satisfactory blade sharpener from steel of such hardness, however, is a matter of considerable difficulty. A blade sharpener of the present type should be capable of being conveniently held in one hand, while the blade is oscillated by the finger of the other. It should therefore not be unduly heavy, and this requirement, as well as the consideration of the cost of the metal, indicates the use of a somewhat thin cylindrical plate, rather than a block of substantial thickness. Steel of the hardness mentioned, however, is very brittle, and if the plate is of a thickness dimension ranging in the neighborhood of say $\frac{1}{16}$ ", there is likelihood of fracture in service, owing to the inherent lack of flexibility in a plate of such thickness. But by making the plate still thinner, for example of a thickness of from .025" to $\frac{3}{32}$ ", there is achieved the requisite lightness in weight and low cost of material, and also sufficient flexibility or "spring," notwithstanding the brittleness of the metal, that the plate will give to the requisite degree, without cracking, while being used. But this choice leads to a further problem, since a simple hardened, cylindrically-shaped steel plate, of the thinness indicated, will invariably warp in course of production, and any slight degree of warping will of course destroy the usefulness of the article. To avoid this occurrence, I form each of the four edges of the plate with a turned stiffening flange. These flanges hold the plate true to form during manufacture and afterwards, and assure a perfectly true surface, such as would otherwise prove impossible to achieve with a plate of the thinness indicated.

As a means for holding the cylindrical sharpening plate during use, I secure to its entire rear-

ward face and to the stiffening flanges a somewhat pliable, flexible or yieldable backing member or block, of a shape suitable for convenient grasping by the hand. This backing or holding member is preferably composed of rubber, vulcanized directly to the back surface of the plate. It is desirable that the backing member have a certain degree of flexibility—sufficient that it will conform to the shape of the thin cylindric plate without exerting substantial warping strains thereon; rubber of a hardness approximating or somewhat exceeding tire rubber is suitable. Use of a backing member of little or substantially no flexibility or yieldability subjects the plate to the effects of undesirable warping strains. Such as may lead to deformation and fracture of the steel plate, which is of such brittleness that it is capable of withstanding but little deflection without cracking.

20 The flexible backing member is incapable of thus warping and so setting up strains in the steel plate such as might lead to cracking. And the plate itself is of such thinness that it is capable of a small degree of deflection without cracking, as stated above, while the stiffening flanges serve not only to restrain warping, but also to restrain the plate against a dangerous degree of deflection during the sharpening operation. The described stiffening flanges, if left of the same hardness as the plate, are liable to cracking off under the pressure exerted in the operation of vulcanizing the rubber backing member to the back of the plate. This difficulty is avoided by annealing the flanges following the 25 hardening of the plate.

With this preliminary discussion in mind, the invention will now be best described by referring to the following detailed description of a present preferred embodiment thereof, reference being 30 directed to the accompanying drawing, in which:

Fig. 1 is a plan view of the sharpener;

Fig. 2 is a transverse section on line 2—2 of Fig. 1;

Fig. 3 is a section on line 3—3 of Fig. 1;

45 Fig. 3a is an enlarged detail taken from Fig. 3; and

Fig. 4 shows the sharpener used as a holder for a razor.

In the drawing numeral 10 designates a hardened, cylindric, steel plate, preferably of a carbon content of from .85 to 1.00%, and hardened to substantially 64+ Rockwell. This plate has a highly polished concave surface 11. The two curved edges of plate 10 are formed with down-turned stiffening flanges 12, and the two side

edges with outwardly turned stiffening flanges 13. The plate, being hardened to the degree indicated, is very brittle, and if the flanges were to be left of the same hardness, they would be very likely to crack off during the procedure of vulcanizing the later described base to the plate. Therefore, after the plate as a whole is hardened, the flanges are annealed, which may readily be done by running a small gas flame along them.

Bonded to the rearward or convex face of cylindric plate 10, and to the inner and under surfaces of the flanges 12 and 13, respectively, is a flexible backing member, holder or base 15, preferably composed of rubber vulcanized directly to the plate, and of a hardness approximating or preferably somewhat exceeding that of tire rubber, though not so hard that the material is capable of warping and so deforming and possibly cracking the plate. In other words, the backing member is of such yieldability or flexibility that it will at all times conform to the curvature of the thin plate, rather than under any circumstances tending to strain or deform the plate by any wrapping tendency of its own.

In the form here shown, the number 15 has a concave upper surface 15^a which lies against the entire under or rearward face of the plate 10, and has end and longitudinal edges 15^b and 15^c which engage the flanges 12 and 13, respectively. The surfaces 15^a, 15^b, and 15^c are intimately bonded to the convex surface of the cylindric plate, and to the flanges 12 and 13, respectively. The block 15 thus being of rubber this is preferably done by vulcanizing, as stated above. The four flanges thus prevent surfaces abutted by the edges of the rubber backing member, and enable a better bond to be secured between the backing member and the plate. The member 15 is preferably and here shown as formed at the bottom with a rectangular or box-like formation defined by integral flanges 16, such as may be conveniently gripped by the hand while the device is in use. Two opposite members of these flanges may be formed with notches 17 for convenient reception of a razor 18 when the device is placed in an inverted position (Fig. 4). This provision affords a handy support on which the razor may be rested when not in use.

The method of use is the same as with prior sharpeners of this general type, except that because of the increased effectiveness of the present article, a substantially lesser number of strokes is required. The razor blade 20 is simply placed in the position of Fig. 3, and then depressed somewhat at the center, and moved back and forth, in the directions indicated in Fig. 3, and also in a direction longitudinally of the cylindric surface. Thus the blade may be given a

sort of oscillatory motion, with components of motion both longitudinally and transverse of the cylindric surface, and as a result of the action of the very hard and highly polished steel surface on the blade edges, the microscopic "teeth" of the blade are quickly re-aligned, as well as honed. A relatively few strokes is sufficient to recondition a blade otherwise ready to be discarded.

As stated in the foregoing, the superior results achieved by the present sharpener are mainly due to the use of a high carbon steel, tempered to extreme hardness. To provide such a surface, I use a very thin cylindric plate, such as will be capable of springing or deflecting slightly in service without cracking, despite the extreme brittleness of steel of such character. To restrain this deflection, and also to restrain deformation or bulging of the surface, the four stiffening flanges are employed. And finally, a backing or base member of a somewhat flexible character is employed to the end that warping of the base, such as would lead to deforming strains, and actual cracking of a plate of such thinness and brittleness as is used, will not occur. These features in combination result in a blade sharpener which is most effective in use, is convenient to handle, and is designed for low cost as well as durability.

I claim:

In a razor sharpener of the character described, the combination of a thin cylindric plate of highly hardened steel, downwardly-turned integral flanges formed along the two curved edges of said cylindric plate, outwardly-turned integral flanges formed along the two side edges of said cylindric plate, said four flanges preserving the form of the cylindric plate after forming, and a base block of rubber or the equivalent that is sufficiently flexible to conform to the shape of the thin cylindric plate without exerting substantial warping strains thereon having a concave face engaging and intimately bonded to the entire under, convex surface of said plate, said rubber block having, at the ends of said concave face, end surfaces formed parallel to said downwardly-turned flanges and abutting and intimately bonded to the inside faces of said flanges, and having, along the longitudinal edges of said concave face, longitudinal upwardly facing edges formed parallel to said outwardly-turned flanges and abutting and intimately bonded to the under faces of said flanges, all so arranged that said block supports the thin cylindric plate and its downwardly and outwardly turned flanges, without exerting substantial warping strains on the plate.

CERTIFICATE OF CORRECTION.

Patent No. 2,280,312.

April 21, 1942.

EMIL H. SCHIPPER.

It is hereby certified that error appears in the printed specification of the above numbered patent requiring correction as follows: Page 2, second column, line 31, beginning with the words "In a razor" strike out all to and including the word and period "plate." in line 57, comprising the claim, and insert instead the following -

-- In a razor sharpener of the character described, the combination of a cylindrical plate of highly hardened high carbon tool steel having a concave sharpening surface, and said plate being of a thickness no greater than substantially one thirty-second of an inch, said plate having curved ends and substantially straight side edges, the curved ends of the plate being formed with downwardly turned integral flanges, said straight side edges having outwardly turned integral flanges, and a rubber base block for supporting said plate, said block being sufficiently flexible to conform to the shape of the thin cylindrical plate without exerting substantial warping strains thereon and having a plain, uninterrupted concave upper face engaging and vulcanized to the adjacent convex surface of said plate, said block having its ends substantially parallel to the downwardly turned flanges on said plate so as to be overlapped by the same and abutting and vulcanized to the inside faces of the downwardly turned flanges, said block having longitudinal side edges overlapped by and abutting the outwardly turned flanges on said plate and vulcanized to said flanges, said flanges along all four edges of the plate constituting stiffening means for preserving the true cylindrical shape of the plate against the effect of warping strains during forming and heat treatment, and presenting surfaces to which said ends and longitudinal side edges of the rubber block may be vulcanized to assure bonding of the block to the plate. --

and that the said Letters Patent should be read with this correction therein that the same may conform to the record of the case in the Patent Office.

Signed and sealed this 16th day of June, A. D. 1942.
